UNITED STATES PATENT OFFICE

93,809

DESIGN FOR A LOCOMOTIVE UNIT FOR A RAILWAY TRAIN

Norman Bel Geddes, New York, N. Y.

Application October 12, 1933, Serial No. 49,472

Term of patent 14 years

To all whom it may concern:

Be it known that I, NORMAN BEL GEDDES, a citizen of the United States, residing in the Borough of Manhattan, city, county, and State of New York, have invented a certain new, original, and ornamental Design for Locomotive Units for Railway Trains, of which the following is a specification, reference being had to the accompanying drawing, forming a part thereof, in which—

Figure 1 is a perspective view of a locomotive unit for a railway train embodying my design, and

Fig. 2 is a diagrammatic transverse section thereof taken on the line 2—2 of Fig. 1.

The dominant feature of my design consists in the form and contour of the casing of the locomotive unit.

I claim:

The ornamental design for a locomotive unit for a railway train substantially as shown and described.

Signed this 11th day of October, 1933.

NORMAN BEL GEDDES.
